(57) **CLAIM**

The ornamental design for a combined earphones and charging case, as shown and described.

DESCRIPTION

FIG. 1 is a perspective view of a combined earphones and charging case, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof;

FIG. 9 is a perspective view of the earphones of the combined earphones and charging case in the charging case; and,

FIG. 10 is a perspective view of the charging case of the combined earphones and charging case in a closed configuration.

The broken lines shown in the drawings depict portions of the combined earphones and charging case that form no part of the claimed design.

1 Claim, 10 Drawing Sheets
